UNITED STATES PATENT OFFICE.

WILLIAM F. WELTER, OF CHICAGO, ILLINOIS, ASSIGNOR TO JOSEPH J. LANZIT, OF CHICAGO, ILLINOIS.

BAILING-MACHINE.

1,056,868.

Specification of Letters Patent. Patented Mar. 25, 1913.

Application filed April 18, 1912. Serial No. 691,647.

To all whom it may concern:

Be it known that I, WILLIAM F. WELTER, a citizen of the United States, residing at Chicago, in the county of Cook and State of Illinois, have invented certain new and useful Improvements in Bailing-Machines, of which the following is a specification, reference being had therein to the accompanying drawing.

10 This invention relates to machines for forming and applying wire bails to paper vessels such as oyster pails, ice cream pails, etc., and consists in the matters hereinafter disclosed and then pointed out in the appended claims.

In the accompanying drawings illustrating a practical embodiment of the various features of the invention Figure 1 is a plan view of a machine embodying the same; Fig. 2 is a front elevation of the machine of Fig. 1; Fig. 3 is a detail view showing the front of the wire gripping mechanism and the bail stripping mechanism; Fig. 4 is a detail view showing the pail-block with a pail thereon and certain of the parts shown in Fig. 3; Fig. 5 is a detail view of the parts shown in Fig. 4 with certain of the parts in section; Fig. 6 is a detail view of the rear of the wire holder; Fig. 7 is a detail view 25 partly in section showing the brake to cushion the wire-bending and driving devices; Fig. 8 is a detail view partly in section showing the staple clenching means in the form block with a pail and bail thereon; and Fig. 9 is a detail view partly in section showing the interior of the form block.

The operating mechanism is suitably mounted and secured on the horizontal table 10, supported by suitable standards or legs 40 11 and having bearings 12 at its rear end for the main driving shaft 13 of the machine which is driven by a pulley 14 from suitable power. The shaft 13 carries a bevel gear 15 which meshes with a bevel gear 16 45 on a counter shaft 17, journaled in suitable supports on one side of the top of the table and carrying a crank-arm 18 which is coupled by a slotted connection to a connecting link 19 pivoted to the inner end of 50 the gripper jaw 20, which is pivoted on a carrier 21 sliding on a fixed track 22 and having a fixed gripper 23 with which the movable jaw coöperates to grip the wire α fed through the straightening rollers 24. 55 The wire extends inwardly beyond the rolls

and beyond a holder secured on the table to prevent the free end of the wire being displaced out of the path of the grippers by the retraction of the cutting plunger. This holder is shown in detail in Fig. 6 and consists of a plate 25 secured upon the inner face of the block 26 in such manner as to allow the wire to pass between these parts. The block is adjustably mounted in a guide-way 27 in the rear face of an upright 28 on the table, and is adjustably set by the headed bolts or lag screws 29 in position so that the wire is severed against its end by the cutting plunger 30. When this plunger 30 is retracted it has a tendency to bend the end 60 of the wire back or away from the block and out of the path of the grippers, and the holder prevents this bending of the wire and retains its end in position for the grippers. When the arm 18 is in the position 65 shown in Fig. 3 the grippers 20 and 23 are in position to engage the end of the wire and as shaft 17 continues to revolve the draft of the connecting link 19 on the inner end of the jaw 20 firmly clamps the 70 wire between the grippers, and as the arm 18 rotates the wire is drawn through its rolls across the machine in the rear of the form block 31, upon which the pail or bucket to be bailed is placed in inverted position, and also in the rear of the bail block 40 upon which the wire is formed into bails. As soon as the arm commences its return 75 movement, the push of the arm on the connecting link 19 causes the jaw 20 to open and release the wire, at which time the bail-holding plate, the bail-forming plungers, and the cutting plunger to sever the wire, are moved to hold, cut off, and bend the wire into bail 80 form to bring the ends of the wire into position to be acted upon by the mechanism to form the staples of the bail and to insert and clench the same within the walls of the vessel to be bailed.

Standards 32 on the table carry a reciprocating plate 33 which carries bail-forming plungers 34 in suitable recesses along the side edges of the plate, these plungers being secured adjustably on the plate by the set screws 35 and forming the bending plungers 90 for the bail. The plate 33 also carries in a suitable dove-tailed groove the slide 36, adjustably connected to a plate 37 by the set screw 38 and sliding independently of the plate 33. The slide 36 is provided with two 100

short ears 39 each provided with a V-shaped groove in its end as shown in dotted lines in Fig. 1. On the table between the form block and the plate 36 is a vertical bail-block 40 provided with two slots 41 in line with the ears 39 on the slide 36, as shown in Fig. 1, and the ears 39 coöperating with the slots 41 in the plate 40 to hold the wire during the bending operation by the plungers 34. The plate 33 carries the cutting-plunger 30 adjustable on its side by the set screws 42, and when the plate 33 is actuated the plunger will be carried forward to bring its angular cutting end against the wire and sever the same against the block 26. The plate 33 is actuated by the engagement of a roller 43 on its inner end with an eccentric groove 44 in the cam disk 45, mounted on the main driving shaft 13. The disk 45 is also provided with a cam surface 46, which engages with a roller 47 on the inner end of the slide plate 37. The action of these cams is timed so that the holding plate 36, the bending plungers 34, and the cutting-plunger 30 move forward just as the wire is released by the grippers, after it is drawn across the machine. The shaft 13 carries a cam-wheel 48 which is provided with an eccentric groove (not shown) actuating a roller in a manner now well understood in the art carried on the upper end of a connecting rod 49, coupled to an arm 50 on a rock-shaft 51 journaled in suitable hangers 52 depending from the table 10. This shaft 51 extends from the rear to the front of the machine, and carries on its forward end as shown in Fig. 2 a lever 53 the ends of which are connected on each side of the links 54 with the levers 55 and 56 respectively pivoted on brackets 57 at each side of the table and whose upper ends are coupled to the reciprocating blocks 58 which carry the staple-forming and driving devices arranged on each side of the form block 31 to insert a staple or end of a bail in each side of the pail or bucket. These blocks slide on rods 59 secured on frames 60 mounted on the table, and the blocks carry plates 61 upon which the staple benders and drivers slide and are guided between the flanges 62. The staple bending and driving devices are of any suitable form and construction and so need not to be herein specifically described beyond stating that they comprise the usual die plates 63 around which the ends of the bail are bent, and the bending plates 64 and driving plates 65 for the staples formed at the ends of the bail. The movement of the levers 56 carries forward the blocks and the plates 64 and 65, and as the plates 64 extend in advance of the plates 65 they give the ends of the wire, which is bent into bail-form on block 40 by the plungers 34, a short right-angle bend against the die plates 63 to form the staples, and as soon

as the staples or end-bends are made the plates 64 stop and the plates 65 continue to advance and drive the staples thus formed through the pail *y* at the same time that the die plates 63 are withdrawn to permit this action. The bail comprises the handle portion *z* and the end staples *z'*, and in order to clench the staples when driven through the pail suitable clenching devices are provided, as shown in Figs. 1, 2 and 8. As shown in Fig. 9 the lower portion of the form block 31 has a chamber 66 for levers 67 connected at one end with a slide 68 which is coupled at its rear end with the lower end of a lever 69 pivoted on a support on the table and having a roller 70 at its upper end engaged by a cam 71 mounted on the shaft 13 so that the slide may be shifted rearwardly at the proper moment by the action of the cam. The slide is returned to its normal position by a coiled spring (not shown) connected between the frame and slide. The form block carries the vertical rock-shafts 72 connected by links 73 at their lower ends to the levers 67, and provided at their upper ends with clenching plates 74 working in an upper recess or chamber 75 of the block in line with the driving plates 65. The cam 71 on the main driving shaft 13 is timed to shift the clenching plates from the position shown in Fig. 2 to the position shown in Fig. 8, just as the ends of the bail forming the staples have been driven through the pail by the drivers 65. The stapling devices are cushioned so as not to strike the wire against the material of the pail hard enough to injure or deface it by driving the sides of the bail more or less into the material by means of a brake which in the present form consists of a brake-band 76 in the form of a split-ring surrounding a leather covered disk 77 on the shaft 51, the brake being secured in place by a bracket 78 depending from the underside of the table 10 and being adjusted by means of a nut 79 threaded on a depending screw 80. The effectiveness of the stroke of the drivers to insert the staples and bend them over on the clenchers is not affected by the cushion, but the blow of the stroke is rendered softer so as not to damage the paper of the pails.

The carrier 21 is provided with a cam plate 80 to release or strip the bail from the bail-block 40; at each forward movement of the carrier the cam plate 80 passes under the body portion of the previously formed bail and lifts it to the position shown in Fig. 5 free of the bail-block so that the pail or vessel may be easily removed from the form-block.

In order to prevent the chamber 75 being clogged or filled by the particles of paper stock carried into it by the staples in passing through the sides of the pail, I provide

a discharge chute 81 in the form block leading down from the center of the chamber 75 to discharge at one side of the block. The movement of the plates 74 tends to move the particles of paper toward the center of the chamber to the outlet.

In the operation of the machine, the pail or vessel *y* to be bailed is placed in inverted position over the form block, and when the machine is set in operation the grippers 5 grasp the end of the wire and draw it forward across the machine in the rear of the form block and bail block. When the grippers release the wire, the cams on the driving shaft carry forward the slide 36 to grasp and hold the wire against the bail block, and the plate 33 which carries the cutting plunger 30 to cut off the wire and the bail-forming plungers 34 to bend the bail around the bail block and bring its ends into position on the die plates 63. The staple formers and drivers then advance and the plates 64 form a right-angle bend in each end of the wire, and the driving plates 63 then continue to advance as the plates 64 are released and drive the staples through the bail and against the clenching plates which with this movement are shifted by the slide 68 to position to coöperate with the drivers to 10 20 25 30 35 40 45 50 55 60 65 70 75 80 85 90 95 100 105 110 115 120 125 130

clench the staples in place. The return of the gripper carrier to its position to again grasp the end of the wire causes the cam plate 80 to strip the bail from the block 40, when the completed pail or vessel is easily removed and another one placed in position for repetition of the work.

I claim:

1. In a bailing machine, the combination of a feeding and stripping mechanism for the wire comprising a sliding carrier, wire-gripping means thereon to engage the wire during the movement of the carrier in one direction, and a bail-stripper on the carrier to raise the bail during the return movement of the carrier, with means for reciprocating said carrier to draw the wire across the machine and to release the same.

2. In a bailing machine, the combination of a feeding and stripping mechanism for the wire comprising a sliding carrier, wire-gripping means thereon, a jaw pivoted thereto to engage the wire during the movement of the carrier in one direction, and a cam on the carrier to raise the bail during the return movement of the carrier, with means for reciprocating said carrier to draw the wire across the machine and to release the same.

3. In a bailing machine, the combination with a form block for holding the vessel to be bailed, a sliding holder for the wire to be formed into the bail, a bail-block at which the wire is held by the holder, reciprocating bail-formers to bend the wire on the bail-block, of a reciprocating carrier for the wire,

and means on the carrier to release the bail from its block when the same is secured to its vessel.

4. In a bailing machine, the combination with a form block for holding the vessel to be bailed, a sliding holder for the wire to be formed into the bail, a bail-block at which the wire is held by the holder, reciprocating bail-formers to bend the wire on the bail-block, of a reciprocating carrier for the wire, and a cam on the carrier to raise the bail off its block when the same is secured to its vessel.

5. In a bailing machine, the combination of a feeding mechanism for the wire, a cutting mechanism comprising a movable cutter and a stationary cutting-block, and a wire-holder on the block to retain the end of the wire in position to be engaged by its feeding mechanism.

6. In a bailing machine, the combination of a feeding mechanism for the wire, a cutting mechanism comprising a movable cutter and a stationary cutting-block, and a holding plate on the block and offset therefrom to allow the wire to pass between the block and plate and retain the end of the wire in position to be engaged by its feeding mechanism.

7. In a bailing machine, the combination of a feeding mechanism for the wire, a bail-block, a sliding plate with a pair of bending plungers and a plunger mounted thereon to cut the wire into bail-lengths, and means to reciprocate the plate.

8. In a bailing machine, the combination of a feeding mechanism for the wire, a bail-block, a sliding plate with a pair of bending plungers and a plunger mounted thereon to cut the wire into bail-lengths, a cutting block having a passageway for the wire in the line of the feeding mechanism, and means to reciprocate the plate.

9. In a bailing machine, the combination of a slide and bail-forming plungers for holding and bending the wire, die blocks around which the staples are formed, staple forming and staple driving means, a shaft and connections therefrom for moving the driving and forming means, and means on the shaft to cushion the stroke.

10. In a bailing machine, the combination of a slide and bail-forming plungers for holding and bending the wire, die blocks around which the staples are formed, staple forming and staple driving means, a shaft and connections therefrom for moving the driving and forming means, and a friction band on the shaft.

11. In a bailing machine, the combination with a form block to hold the vessel to be bailed and provided with a chamber having a discharge outlet, staple forming and driving means to form and drive the staples through the vessel, and clenching plates piv-

totally mounted in the chamber in the form block, and means for shifting the clenching plates when the ends of the bail are driven through the vessel.

- 5 12. In a bailing machine, the combination with a form block to hold the vessel to be bailed and provided with a chamber having a central and downwardly directed discharge passage, staple forming and driving means
10 to form and drive the staples through the vessel arranged in pairs on each side of the

form block, clenching plates pivotally mounted in the chamber of the block at the sides of its said passage, and means for shifting the clenching plates when the ends 15 of the bail are driven through the vessel.

In testimony whereof I affix my signature in presence of two witnesses.

WILLIAM F. WELTER.
